UNITED STATES PATENT OFFICE.

ELMER J. ANDERSON, OF PROPHETSTOWN, ILLINOIS.

GOVERNOR.

1,402,994.

Specification of Letters Patent. Patented Jan. 10, 1922.

Application filed March 15, 1920. Serial No. 365,962.

To all whom it may concern:

Be it known that I, ELMER J. ANDERSON, a citizen of the United States, residing at Prophetstown, in the county of Whiteside 5 and State of Illinois, have invented new and useful Improvements in Governors, of which the following is a specification.

This invention relates to means for controlling the speed for an internal combustion engine by a governor and the principal 10 object of the invention is to provide a governor attachment for use on tractors when the tractor is being used for belt work.

Another object of the invention is to provide 15 means for adjusting the parts so that the governor will act at any desired speed.

Still another object of the invention is to provide means for running the governor by a belt which is passed over the fan belt so 20 that said governor may be quickly and easily rendered active or inactive.

This invention also consists in certain other features of construction and in the combination and arrangement of the several 25 parts, to be hereinafter fully described, illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a diagrammatic side view 35 showing my invention in use on the motor of a tractor.

Figure 2 is a front view.

Figure 3 is a sectional view through the 40 governor means.

Figure 4 is a cross sectional view through such means.

Figures 5, 6 and 7 are detail views.

In these views 1 indicates the motor which is provided with the usual carburetor 2, the 45 throttle on said carburetor being controlled by the throttle rod 3. The pulley 4 on the crank shaft of the engine is connected with the fan pulley 5 by the belt 6 as usual.

In carrying out my invention I provide 50 a bracket 7 which is held in place by two large bolts on the timer gear housing. This bracket is provided with an arch 8 in which is journaled the governor 9. This governor may be of any desired construction and will 55 not be described in detail. This governor carries a gear 10 which is in mesh with a

gear 11 on the horizontal shaft 12, journaled in the bracket, and carrying at its outer end the pulley 13. A belt 14 passes over this pulley and over the pulleys 4 and 5, a part of said belt engaging a part of the belt 6. A pulley 15 is adjustably mounted on the lower part of the bracket for placing tension on the belt 14 and holding said belt out of contact with a part of the motor. It 65 will thus be seen that when the belt 14 is in place the governor will be actuated by the motor.

A horizontal shaft 16 is placed at one side of the motor with its front end journaled 70 in the bracket 7 and its other end journaled in a bracket 17 which is suitably attached to the rear part of the motor. This shaft has connected thereto an arm 18 which projects under the vertically movable rod 19 75 of the governor so that as the weighted arms of the governor swing outwardly and move said rod downwardly it will swing the arm 18 downwardly and thus rock the shaft 16. This shaft is connected with the 80 throttle rod 3 by means of the rods 20 and 21. One of these rods is adjustably connected with the shaft 16 by the sleeve 20' formed at its lower end by the set screw 20*. The upper end of this rod is connected 85 with the lower end of the rod 21 and the upper end of the rod 21 is detachably connected with the bracket 22, said bracket being clamped to the rod 3 so that it may be adjusted on said rod. 90

It will thus be seen that as the shaft is rocked by the governor the throttle rod will be also rocked and thus the throttle actuated to reduce the speed.

The arm 18 is kept in engagement with 95 the governor rod by means of a spring 23 on the projecting end of the shaft and having one end connected therewith and its other end connected to a small ratchet wheel 24 on said shaft. This ratchet wheel is 100 held in adjusted position by a dog 25 connected with a part of the bracket. By this means the tension of the spring can be adjusted so that the action of the governor on the shaft may be controlled. 105

The governor may be thrown out of action by removing the belt 14 or the shaft 16 may be disconnected from the throttle rod by disconnecting the rods 20 and 21 from the shaft. 110

My device is primarily intended for use when the tractor is being used for belt work,

and will prevent racing of the motor when the load is removed. It also acts to keep the motor running at a uniform speed, such speed being regulated by the tension placed 5 on the spring.

It is thought from the foregoing description that the advantages and novel features of my invention will be readily apparent.

I desire it to be understood that I may 10 make changes in the construction and in the combination and arrangement of the several parts, provided that such changes fall within the scope of the appended claims.

What I claim is:—

15 1. In combination with an internal combustion motor and its fan driving means, a bracket supported by the motor frame, a governor supported by said bracket, a shaft geared to said governor and journaled in the bracket, a pulley on said shaft, a belt connecting said pulley with the fan driving means, a rock shaft having one end journaled in the bracket, a second bracket supported by the motor frame in which the other end

of the shaft is journaled, an arm on said 25 shaft extending under the governor rod, means for adjusting the action of the governor on said shaft and means for connecting said shaft with the throttle rod.

2. In combination with an internal com- 30 bustion motor and its fan driving means, a bracket connected with the front of the motor frame, a governor carried by said bracket, a shaft journaled in said bracket and geared to the governor, a pulley on said shaft, 35 means for connecting the pulley with the fan driving means, a bracket supported at the rear of the motor frame, a rock shaft journaled in the brackets; arms connecting said shaft with the throttle rod, an arm 40 on said shaft extending under the governor rod, a spring on said shaft having one end connected thereto, a ratchet wheel on the shaft connected with the other end of the spring and a dog for holding said wheel in 45 adjusted position.

In testimony whereof I affix my signature.
ELMER J. ANDERSON.
